UNITED STATES PATENT OFFICE

STANLEY CRAIG HOPE, OF SPRINGFIELD, MASSACHUSETTS

SAFETY RAZOR

Original application filed September 15, 1927, Serial No. 219,748. Divided and this application filed
August 15, 1928. Serial No. 299,755.

My invention relates to safety razors, and particularly to means for storing extra blades in, and withdrawing them singly for use from the handle.

5 My invention comprises with other features, a special magazine for holding a number of blades, means for placing and retaining the magazine in the handle, and means for withdrawing the blades singly from the magazine and handle.

10 In order that my invention may be fully understood, I will first describe in detail the mode in which I at present, prefer to carry the invention into practice, and then particularly point out the novel features of the invention in the claims.

15 Reference is to be had to the accompanying drawings forming part of the application in which like parts are designated by the same 20 letters in all the figures.

Figure 1 is a cross-sectional view of the handle of a safety razor, embodying my invention, showing the blades stored in the handle.

25 Figure 2 is a cross-sectional view of the handle showing one blade being withdrawn.

Figure 3 is a sectional view on the line 3—3, Figure 1.

30 In the drawings, number 7 designates the handle of the razor, which is hollow, and open at its lower end, and is provided with a removable cap 8 fitted over its lower end for closing it. A bayonet lock 9 is, by preference provided, for securing the cap 8 removably 35 on the open end of the handle.

To provide for storing a package of blades in the hollow handle 7, and for removing the blades therefrom singly as needed, I prefer to pack a number of blades 15 in a special 40 case 28, of wood or other light and cheap material, having a medial axial squared bore 29 open at both ends, and opening forwardly through a narrower slot 30 in its front wall 31.

45 The packed blades are pressed against the inside of the front wall 31, by a longitudinal strip 32, acting as a follower, bearing against the rearmost blade and pressed thereagainst by springs 33 held in recesses 34 in 50 the back of the bore 29, and pressing against

both ends of the follower 32. All the blades in the case 28, except the foremost blade are held against longitudinal displacement in the case by a cover 35 screwed over the open bottom of the case, and having a slot 36, in longitudinal alignment with the foremost blade, to permit the same to be ejected therefrom. 55

The cap 8 is likewise provided with a blade-ejection slot 37, in longitudinal alignment with the slot 36 in the magazine or case cover 35. The follower 32 is tapered at both ends on its face as shown at 39, away from the front wall 31, to facilitate the introduction of the blades between the follower and the front wall 31. 60

65 The case or magazine 28 containing the blades is fitted to and inserted in the front portion of the tubular handle 7. In the rear portion of said handle is fitted to slide longitudinally, a blade ejection carrier 40, to the face of which is attached a spring arm 41 having on its upper end a blade hook 42, which projects through and rides in the slot 30 in the wall of the case. The blade hook 42 projects forwardly enough to engage the upper edge 70 of one blade only, and to the back of the carrier 40 is attached an ejector button 44, by a screw 43, projecting through and riding in a longitudinal slot 45, formed in the rear of the handle wall. 75

80 The ejector carrier 40, is normally pressed upward by a coiled spring 46, inserted in a tubular guide 47 forming the lower portion of the carrier, the upper end of the spring bearing against the solid upper head 48 of the carrier, and the lower end of the spring bearing against a plunger 49, fitted loosely in the tubular carrier guide 47, and having a stem 50 projecting through the constricted lower opening 51 of the guide and resting on the inside of the handle cap 8, to hold the same 85 against turning. 90

Thus, by simply depressing the button 44 with the finger, a single blade is easily ejected so that it can be withdrawn by hand from 95 the handle through the slots 36 and 37, for use in the clamping head of the razor as previously described.

It is evident that many changes may be made in the specific construction and arrange- 100

ment of my invention herein described without departing from the boundaries thereof as defined by the following claims.

This application is a division of my prior application for patent, Serial No. 219,748, filed September 15th, 1927.

I claim as my invention:

1. A safety razor comprising a tubular handle having a removable cap with a blade ejection opening at its lower end, a case for packing a number of blades in the handle having a removable cover with a blade-ejection opening in its lower end registering with the ejection opening in the cap, and means for ejecting a single blade through the openings in the lower ends of the handle cap and case cover.
2. A safety razor as specified in claim 1, in which the lower end of the blade-case is closed by a detachable cover having a blade-ejection opening.
3. A safety razor as specified in claim 1, in which the blade ejector consists of an ejector carrier sliding longitudinally in the handle outside the blade-case, a spring ejector arm having a blade hook projecting through the case opening over one blade only, and a carrier elevating spring below the carrier.
4. A safety razor as specified in claim 1, in which the ejector carrier has a tubular extension guide, and a plunger and intervening carrier spring are fitted loosely in said tubular guide.
5. A safety razor as specified in claim 1, in which the ejecting means comprise an ejector carrier having a tubular guide with a constricted lower opening and a plunger having a stem projecting through said opening and bearing on the lower handle cap.
6. A safety razor as specified in claim 1, in which the tubular handle has a longitudinal side opening, and the ejecting means comprise an interior ejector carrier and an operating button sliding outside the handle and connected through the handle opening with the interior ejector carrier.

In testimony whereof I affix my signature.

STANLEY CRAIG HOPE.
